SURFACING MACHINE

Paul L. Wagner, Walnut Creek, Calif.

Application December 2, 1950, Serial No. 198,829

5 Claims. (Cl. 51—170)

1

My invention relates to surfacing machines and more particularly to a portable machine capable of use in sanding and buffing surfaces.

Among the objects of my invention are:

(1) To provide a novel and improved surfacing machine;

(2) To provide a novel and improved portable surfacing machine capable of use in sanding and buffing surfaces;

(3) To provide a novel and improved portable surfacing machine adaptable for operation from the drill chuck of a portable electric drill;

(4) To provide a novel and improved portable surfacing machine requiring no gears or pinions;

(5) To provide a novel and improved portable surfacing machine of simple but rugged construction;

(6) To provide a novel and improved portable surfacing machine offering a firm grip and control to the operator;

(7) To provide a novel and improved surfacing machine adapted to reach into corner spaces not accessible to other types of surfacing machines;

(8) To provide a novel and improved sanding machine which does not leave large swirls or circles on the sanded surface.

Additional objects of my invention will be brought out in the following description of a preferred embodiment of the same taken in conjunction with the accompanying drawings wherein

Figure 1 is a three-dimensional view of a surfacing machine embodying the features of the present invention;

Figure 2 is a plan view of the machine of Figure 1 with the cover removed to expose interior construction;

Figure 3 is a view in section taken in the plane 3—3 of Figure 2; and

Figure 4 is a view in section taken in the plane 4—4 of Figure 2.

Referring to the drawings for the details of my invention in its preferred form, the same utilizes a surfacing plate 1 to which is removably affixed surfacing material such as a sheet 3 of sandpaper or buffing cloth, or the like, as the case may be, such material being applied in any suitable manner. In the specific embodiment illustrated, the sheet of the material is folded over the side edges of the plate and maintained taut by clips 5 interconnected by coil springs 7. A layer 9 of felt or other resilient material covering the under surface of the plate serves to cushion the sheet of sanding or buffing material

and allows it to conform to slight irregularities in the surface being worked on.

The plate is oscillatable with respect to a drive shaft support or housing 11 mounted thereon and which encloses the operating mechanism of the machine. The housing is of hollow cylindrical form and is journaled about a bearing disk 13 which is solidly affixed to the upper surface of the plate substantially centrally thereof by a plurality of machine screws 15. A pair of such screws in diametrical relationship to each other have laterally perforated heads to serve as anchors for the lower ends of a pair of coil springs 17, which at their upper ends encircle a diametrically mounted cross-bar 19 in the upper region of the housing. The springs as thus installed serve to hold the housing to the plate while at the same time permitting the desired oscillatory movement of the plate with respect to the housing.

A drive shaft 21 entering the housing at a vertical angle and normal to the cross-bar 19, is journaled at opposite points in the circular wall of the housing. This shaft carries a cam 23 in contact with the upwardly directed parallel arms 25 of a U-shaped yoke 27 which rests on and is pivotally affixed to the bearing disk as by a screw 28 whereby the yoke may be deemed to be pivotally connected to the plate itself.

The upper rim of the housing is recessed and undercut to receive disk cap or cover 29 which is retained in position by the circular retainer spring 31.

In utilizing the machine for its intended purposes, it is securely grasped with one hand about the housing which enables a firm grip to be had, and power is applied to the drive shaft. The accompanying rotation of the cam between the arms of the yoke transforms the rotational movement of the drive shaft into oscillatory movement of the plate. In this connection, the pivotal mounting of the yoke permits the yoke to oscillate with rotational movement of the cam to preclude binding of the cam in the yoke.

Power may be derived through a flexible cable coupled to the drive shaft; or the drive shaft may be clamped in the drill chuck 33 of a portable electric drill and driven in this manner.

While the plate 1 is preferably rectangular in form and of a size to take standardized squares of sandpaper, additional sanding surface may be had by adding to the front end of the plate, a section 35 whose edge is preferably arched on a circle coinciding with the arc of movement of the front corners of the plate.

The device as thus illustrated and described may be manufactured very economically in that it is entirely devoid of gears and pinions and requires but a minimum of parts and otherwise fulfills the objects of my invention as previously noted.

Although I have disclosed my invention in its preferred form and in considerable detail, the same is subject to alteration and modification without departing from the underlying principles involved, and I accordingly do not desire to be limited in my protection to the specific details illustrated and described except as may be necessitated by the appended claims.

I claim:

1. A surfacing machine comprising a flat plate adapted to receive surfacing material on its underside, means for removably securing such surfacing material to said plate, a drive shaft support rotatively mounted with respect to said plate to permit oscillatory movement of one relative to the other, a drive shaft journaled in said support at an angle to the vertical with said plate in a horizontal plane, a yoke, means connecting said yoke to said plate in off-center relationship to the center of such oscillatory movement and in straddling relationship to said drive shaft, and a cam on said drive shaft in contact with both arms of said yoke.

2. A surfacing machine comprising a flat plate adapted to receive surfacing material on its underside, means for removably securing such surfacing material to said plate, a drive shaft support rotatively mounted on said plate to permit oscillatory movement of one relative to the other, a drive shaft passing through said support at an angle to the vertical with said plate in a horizontal plane and journaled therein, a yoke, means connecting said yoke to said plate in off-center relationship to the center of such oscillatory movement and in straddling relationship to said drive shaft, and a cam on said drive shaft in contact with both arms of said yoke.

3. A surfacing machine comprising a flat plate adapted to receive surfacing material on its underside, means for removably securing such surfacing material to said plate, a drive shaft support on said plate disposed substantially centrally thereof, a bearing intervening between said plate and said support to permit oscillatory movement of one relative to the other, a drive shaft passing through said support at an angle to the vertical with said plate in a horizontal plane and journaled therein, a yoke, means connecting

5 arms of said yoke.

4. A surfacing machine comprising a flat plate adapted to receive surfacing material on its underside, means for removably securing such surfacing material to said plate, a bearing immovably affixed to said plate, a cylindrical housing journaled on said bearing, and means for oscillating said plate with respect to said housing, said means involving a drive shaft entering said housing at an angle to the vertical with said plate in a horizontal plane and journaled at opposite points in the wall thereof, a yoke affixed to said bearing in off-center relationship to said cylindrical housing and in straddling relationship to said drive shaft, and a cam on said drive shaft in contact with both arms of said yoke.

5. A surfacing machine comprising a flat plate adapted to receive surfacing material on its underside, means for removably securing such surfacing material to said plate, a disk bearing immovably affixed to the upper surface of said plate, a cylindrical housing journaled on said disk bearing, and means for oscillating said plate with respect to said housing, said means involving a drive shaft entering said housing at an angle to the vertical with said plate in a horizontal plane and journaled at opposite points in the wall thereof, a yoke affixed to said disk bearing in off-center relationship to said cylindrical housing and in straddling relationship to said drive shaft, and a cam on said drive shaft in contact with both arms of said yoke.
